UNITED STATES PATENT OFFICE.

HENRY A. AHRENS, OF CLEVELAND, OHIO, ASSIGNOR TO THE H. FRANKE STEEL RANGE COMPANY, OF CLEVELAND, OHIO, A CORPORATION OF OHIO.

COOKING-RANGE.

1,141,748.

Specification of Letters Patent.

Patented June 1, 1915.

Application filed October 19, 1914. Serial No. 867,319.

To all whom it may concern:

Be it known that I, HENRY A. AHRENS, a citizen of the United States, residing at Cleveland, in the county of Cuyahoga and State of Ohio, have invented a certain new and useful Improvement in Cooking-Ranges, of which the following is a full, clear, and exact description.

This invention relates to certain improvements in cooking ranges which have connected with the range proper a hinged leaf carrying a gas burner which, when the leaf is in a horizontal position, may be used to heat cooking vessels supported upon said leaf.

The object of the invention is to provide means by which, when said auxiliary gas burners are in use, the products of combustion therefrom will be conducted into the space within the range below the range top, whereby the heat from said products of combustion will be utilized to heat a part of the range top, and whereby also said products of gas combustion will be directed into the stove pipe hole of the stove, instead of being allowed to escape into the room,— and to accomplish these results by means which do not impair the efficiency of the range proper when the drop leaf is down and out of use.

The invention consists in the construction and combination of parts shown in the drawing and hereinafter described and pointed out definitely in the appended claims.

In the drawing, Figure 1 is a plan view partly sectioned of a cooking-range having a drop leaf carrying gas burners, embodying the invention. Fig. 2 is a front view of the same, partly broken away. Fig. 3 is a sectional front elevation. Fig. 4 is a perspective view of the damper carrying flue which is to be attached to the end of the range; and Fig. 5 is a rear view thereof.

Referring to the parts by letters, A represents an ordinary cooking range which may be constructed to burn coal, gas, or any other fuel.

a represents the top of the range; and a' a space below the same which is in communication with the stove pipe hole a^3 . This space is, of course, in open communication with the fire pot a^2 of the range, and is the space through which the products of combustion of fuel by the range will flow

on its way to the smoke pipe hole, with the result of heating the stove top above said space.

B represents the drop leaf which is a shallow box-like construction, preferably built up of sheet metal. Within this box-like drop leaf and in a plane below the top plate b thereof, one or more gas burners C of suitable construction are secured. Each burner is provided with a supply pipe c , the end of which extends to the front edge of the leaf B. Gas nozzles d , which are supported by the auxiliary gas supply pipe D, project into the flaring ends of these supply pipes, and are the means for injecting gas thereto. The flow of gas to each nozzle may be controlled by a valve d^1 . The auxiliary gas supply D to which gas controlled nozzles are attached has a hinge connection d^2 with the main gas supply pipe D^1 . This hinge itself may be of familiar form, such that it serves as a valve which is open for the passage of gas when the auxiliary pipe D is in the horizontal position, but is closed to prevent such passage of gas when said auxiliary pipe occupies the down hanging vertical position indicated by dotted lines in Fig. 3.

Fixed to the under side of the overhanging part of the top plate b of the drop leaf are two downwardly extended ears b^3 . Two curved arms E are fixed to the under side of the overhanging edge of the top plate a of the range. Their ends are connected by pivoted bolts e with ears b^3 of said drop leaf. The axis of these pivot bolts should be alined with the axis of the hinge which connects the two gas pipes D, D^1 . Suitable means, as, for example, two brackets F, which are hinged to the end plate a^4 of the range may be employed to hold the drop leaf in the horizontal operative position, or allow it to swing down into a vertical position.

So much of the construction shown in the drawing as is above described is not original with me. My invention resides in the now to be described additions thereto by means of which the desired results are secured.

A hole a^5 , preferably rectangular and horizontally elongated, is formed through the end wall a^4 of the range in a plane between the top plate a and the horizontal plane in which lie the axes of the pivot bolts

e. Over this slot or hole a correspondingly shaped outwardly projecting draft flue G is secured. In that end of the box-like drop leaf which is adjacent to the end plate α^4 , when the leaf is in a horizontal position, a slot or opening b^5 is cut, in such position that it will register with the open outer end of said draft flue when the drop leaf is in the horizontal position. In fact, the end of 10 said draft flue will then project slightly into this hole. Within this draft flue an automatically closing damper H is placed. This is provided at its other edge with integral pivot studs h by means of which it is pivoted to the draft flue in such manner that gravity causes it to close itself. To a projecting end of one pivot stud h an arm h^1 is fixed. A stud J is fixed to the adjacent end of the drop leaf for engagement with this arm h^1 , and in such position that when 20 the drop leaf is swinging up to its horizontal position this stud will engage this arm and will swing the damper open. The products of combustion from the burners in the drop leaf will pass through this open 25 draft flue into the space α^2 within the range below the top plate α thereof, and will, of necessity, impart some of its heat to the top plate of the stove; and these products of 30 combustion will escape from this space into the stove pipe through the same hole α^3 that the products of combustion from the fire pot of the range escape. When the drop leaf is swung down out of use, the damper 35 H automatically closes and thereby prevents the escape through flue G of the products of combustion of fuel in the range proper.

Having described my invention, I claim:

1. A cooking range having below its top 40 and in communication with the stove pipe hole thereof a space through which the heated products of combustion in said stove will flow to said stove pipe hole, a box-like drop leaf which contains a gas burner and is 45 hinged to the stove at one end thereof on an axis which is below the top of the stove and below the top of the drop leaf,—which

box-like drop leaf has a hole through that side which is adjacent to the stove when the drop leaf is in a horizontal position, 50 which hole is above the axis on which the drop leaf is hinged, and means for supplying gas to said burner when the drop leaf is in its horizontal position, combined with a flue box fixed to the adjacent end of the 55 stove and projecting therefrom toward the drop leaf above the hinge axis of said drop leaf and in position to register with the hole in said drop leaf when the latter is in the horizontal position, and a damper in said 60 flue box.

2. A cooking range having below its top and in communication with the stove pipe hole thereof a space through which the heated products of combustion in said stove will 65 flow to said stove pipe hole, a box-like drop leaf which contains a gas burner and is hinged to the stove at one end thereof on an axis which is below the top of the stove and below the top of the drop leaf,—which 70 box-like drop leaf has a hole through that side which is adjacent to the stove when the drop leaf is in a horizontal position, which hole is above the axis on which the drop leaf is hinged, and means for supplying gas 75 to said burner when the drop leaf is in its horizontal position, combined with a flue box fixed to the adjacent end of the stove and projecting therefrom toward the drop leaf above the hinge axis of said drop leaf 80 and in position to register with the hole in said drop leaf when the latter is in the horizontal position, a self closing damper in said flue box having an operating arm secured to said damper, and a projection on said 85 drop leaf adapted to engage and move said arm, and thereby open the damper as the drop leaf swings to its horizontal position.

In testimony whereof, I hereunto affix my signature in the presence of two witnesses. 90

HENRY A. AHRENS.
